United States Patent Office.

JOHN ELBERTSON, OF KIRKSVILLE, MISSOURI.

Letters Patent No. 77,016, dated April 21, 1868.

IMPROVED CARTRIDGE-BOX.

The Schedule referred to in these Letters Patent and making part of the same.

TO ALL WHOM IT MAY CONCERN:

Be it known that I, JOHN ELBERTSON, of Kirksville, in the county of Adair, and State of Missouri, have invented a new and improved Cartridge-Box; and I do hereby declare that the following is a full, clear, and exact description of the construction and operation of the same, reference being had to the annexed drawings, making a part of this specification, in which—

My invention is represented by a perspective view, a portion of the near wall of the box being removed in order to show its interior.

In this invention the cartridges are arranged in a circular disk, which is hung at its centre upon a spindle in a circular case. The latter is provided with a door at its lower edge, by which the cartridges are taken out. The disk carries the percussion-caps also, which are taken out through a port in the upper side of the case. The disk and case are so constructed and arranged that the cartridges and caps will always present themselves at the proper place to be handled.

In the drawings, A represents the circular case, having a door, B, on its front side, near the lower edge, and another, C, on its rim, at the top. This case forms the body of the cartridge-box, being supported on the person by means of a belt, which passes under and partially around it, through the eyes or clasps a a. Inside of this case is a circular disk, E, revolving freely on a pin or bolt, E', which passes through its centre, and provided with lateral chambers or recesses e e, to hold the cartridges, and with split studs or nipples n n around its perimeter, to hold the percussion-caps, the object of the split in the nipples being to allow their sides to spread apart, and thus more securely confine the caps, and prevent their falling off. The inner walls of the case may be lined with flannel or other suitable substance, to protect the cartridges and caps from accidental firing. The walls of the disk may also be covered with the same material, if thought necessary. The apertures B and C may be covered with a single flap of leather, or with any kind of door that may be preferred. The case may be constructed of sheet metal, or of wood.

The operation of a cartridge-box thus constructed will be as follows: As soon as a cartridge is removed, that side of the disk will become lighter than the other sides, and will rise to the top of the case, presenting the opposite edge of the disk, full of cartridges, to the door B, so that when the soldier next handles his cartridges he will find them in the proper position at the door of the case, and ready for use. He will not, therefore, be obliged to spend time in examining his cartridge-box to find the cartridges, but will always place his thumb and fingers at one point in the box, and, so long as there are cartridges left, will find them at that point.

Having thus described my invention, what I claim as new, and desire to secure by Letters Patent, is—

1. The self-adjusting disk E, for holding the cartridges or caps, when used in combination with an enclosing case, substantially as and for the purpose specified.

2. I claim the split nipples n n, having their sides springing slightly apart, for the purpose of holding the caps, in the manner described.

To the above specification of my invention I have signed my hand, this 25th day of February, 1868.

JOHN ELBERTSON,
